UNITED STATES PATENT OFFICE.

EMIL V. DITTLINGER, OF ST. LOUIS, MISSOURI.

DESIGN FOR AN ENGINE OR MOTOR FRAME.

SPECIFICATION forming part of Design No. 35,538, dated December 31, 1901.

Application filed November 11, 1901. Serial No. 81,959. Term of patent 7 years.

To all whom it may concern:

Be it known that I, EMIL V. DITTLINGER, a citizen of the United States, and a resident of the city of St. Louis, State of Missouri, have invented and produced a new and original Design for an Engine or Motor Frame, of which the following is a full, clear, and exact description, reference being had to the accompanying drawings, forming a part hereof.

The material or essential feature of my design consists of a rectangular central portion 1, rigid with which are the twelve-sided end portions 2, which are of equal size and rigid with the ends of the vertical extensions 3, the lower ends of which are turned horizontally. A circular elevation 5 is integral with the upper side of each of the twelve-sided extensions 2, and smaller circular projections 6 extend from the sides of the said extensions 2.

The circular projections 7 extend from the lower sides of the extensions 2 in vertical alignment with the extensions 5. A large circular elevation 8 projects from one side of the rectangular central portion 1, and a smaller and somewhat-tapering tubular projection 9 extends from the opposite side of the said rectangular portion.

10 indicates a number of smaller and shorter projections, which extend from the rectangular portion 1 at equal distances from the tubular projection 9.

I claim—

The design for an engine or motor frame, substantially as herein shown and described.

In testimony whereof I affix my signature in presence of two witnesses.

EMIL V. DITTLINGER.
